T. H. NASH,

APPARATUS FOR REFINING PULP STUFF AND THE LIKE.

APPLICATION FILED JULY 24, 1914.

UNITED STATES PATENT OFFICE.

THOMAS HENRY NASH, OF ST. PAULS CRAY, ENGLAND.

APPARATUS FOR REFINING PULP STUFF AND THE LIKE.

1,140,181.

Specification of Letters Patent.

Patented May 18, 1915.

Application filed July 24, 1914. Serial No. 852,907.

To all whom it may concern:

Be it known that I, THOMAS HENRY NASH, a subject of the King of Great Britain and Ireland, and a resident of Garland Hill, St. 5 Pauls Cray, Kent, England, have invented certain new and useful Improvements in Apparatus for Refining Pulp Stuff and the like for Use in the Manufacture of Paper and the like; and I do hereby declare the 10 following to be a full, clear, and exact description of the same.

This invention relates to improvements in apparatus for refining torn rags, pulp, stuff and the like for use in the manufacture of 15 paper.

My invention has for its object to provide a simplified construction and combination of apparatus which requires less driving power, and expedites the treatment, and 20 which comprises units performing their own work or functions independently of the others, and enabling their operations to be better regulated.

According to my invention, I provide a 25 container for mixing the stuff and which may be adapted to automatically eliminate or separate pieces of metal or other heavy objects in the stuff, a beating engine comprising one or more beater rolls and ar- 30 ranged approximately on a level with the container and in such manner that the stuff gravitates through the beating engine, a regulable chute or gate connecting the beating engine with the container, and a circu- 35 lator or other means and an uptake for returning the stuff from the beating engine to the container.

In the operation of the improved means, the supply of stuff to the beating engine can 40 be regulated by the chute or gate in such manner that an even beating action and even driving power is required.

My invention is illustrated, by way of example, in the accompanying drawings, in 45 which:—

Figure 1 is an elevation; and Fig. 2 is a plan.

In the drawings, the numeral 3 indicates a container for mixing the stuff, having a 50 depressed, well-shaped or semi-circular bottom, 4, and a zig-zag-like mixing frame or agitator, 5, rotatably mounted in bearings in the ends of the container. Pieces of iron or other heavy objects in the stuff descend 55 to the lowest part of the container bottom

and are not liable to pass to the stuff outlet, hereinafter referred to.

At a level somewhat above the lowest point of the container is a stuff outlet, 6, which communicates with one end of a 60 chute 7, the other end of which opens on to an inclined feed plate, 8, of a beating engine. The outlet, 6, from the container is furnished with an adjustable gate or valve, 9, so that the amount of stuff flowing to the 65 beating engine can be readily regulated.

The beating engine may comprise one or a plurality of beater rolls, 10, and the inclined feed plate or bottom, 8, of the latter discharges the material into the intake, 11, 70 of a circulator, 12, by which it is forced through a pipe, 13, back to the opposite end of the container, 3, from which it was discharged, wherein it is remixed, and whence it is redischarged for repeated treatment. 75

It will be noticed that the mixing container and beating engine are on the same floor, and that but little power is required to work the circulator. Further, that the supply of stuff to the beating engine is independent of the circulator, which is merely used to return the stuff from the beating engine to the mixing container, the stuff gravitating through the beating engine. 80

The beater rolls may be adjusted with 85 regard to the bed plate by levers, 14, or screws, in any convenient manner. The mixing frame or agitator, 5, may be driven by gearing, 15; the beater rolls may be driven by pulleys, 16; and the circulator 90 may be driven by pulleys, 17.

The pulleys of the beater rolls are preferably arranged between bearings, so that the pull of the driving belt may help to retain the rolls in place. The container, the casting of the beating engine and the chute are 95 preferably constructed of non-metallic material to prevent the stuff from becoming soiled as happens when iron or the like is employed in their structure and comes into 100 contact with the stuff.

What I claim as my invention and desire to secure by Letters Patent is:—

1. Apparatus for refining pulp, stuff and the like for use in the manufacture of paper 105 comprising, in combination, a mixing container, a beating engine arranged approximately on a level therewith and in such manner that the stuff gravitates through the beating engine, a regulable chute connecting 110

the container to the beating engine, a circulator connected to the beating engine, and an uptake connecting the circulator to the container, for returning the stuff from the 5 beating engine to the container, substantially as described.

2. Apparatus for refining pulp, stuff and the like for use in the manufacture of paper comprising, in combination, a mixing container, a beating engine arranged approximately on a level therewith, a chute connecting the container to the beating engine, an adjustable valve for controlling the amount of stuff flowing from the container through 10 the chute to the beating engine, and means for returning the stuff from the beating engine to the container, substantially as described.

3. Apparatus for refining pulp, stuff and 20 the like for use in the manufacture of paper comprising, in combination, a mixing container, a beating engine arranged approximately on a level therewith, a regulable chute connecting the container to the beating 25 engine, said beating engine having an

inclined feed plate, and means for returning the stuff from the beating engine to the container, substantially as described.

4. Apparatus for refining pulp, stuff and the like for use in the manufacture of paper 30 comprising, in combination, a mixing container, a beating engine arranged approximately on a level therewith and comprising a plurality of beater rolls and a plurality of bed plates arranged in tandem, inclined 35 feed plates leading to each beater roll and bed plate, a regulable chute connecting the container to the first feed plate, means for independently adjusting the beater rolls with regard to the bed plates, and means 40 for returning the stuff from the beating engine to the container, substantially as described.

In testimony whereof I affix my signature, in presence of two subscribing witnesses.

THOMAS HENRY NASH.
